ATTORNEY

UNITED STATES PATENT OFFICE.

SETH A. CRONE, OF EAST ORANGE, NEW JERSEY.

RAILWAY BRAKE BEAM.

Application filed February 12, 1924. Serial No. 692,294.

To all whom it may concern:

Be it known that I, SETH A. CRONE, a citizen of the United States, and a resident of East Orange, in the county of Essex and **5** State of New Jersey, have invented certain new and useful Improvements in Railway Brake Beams, of which the following is a specification.

The invention pertains to trussed brake beams and particularly to a four-point suspension therefor employing inclined tramway bars extending outwardly from the spring plank or channel of the car truck to support and guide the truss rods during the **15** movements of the beams to carry the brake-shoes toward and from the car-wheels.

Four-point suspension tramway-bars for guiding a brake-beam and assuring the proper application of the brake-shoes to **20** and their release from the wheels are well known, and one example of such bars is shown in Letters Patent No. 1,475,280, granted to me on November 27, 1923.

My present invention pertains to novel **25** means for detachably clamping the suspension tramway bars to the spring plank or truck-channel, and also to the combination therewith of certain safety guard or link-bars which extend outwardly therefrom **30** above the end portions of the brake beam and the tramway bars below the same and are detachably connected with the outer ends of said bars, said safety guard bars serving in the event of accident to the usual **35** brake-hangers, to prevent the brake-shoes from being carried unduly upward by the car wheels on a service application of the brakes.

The clamping means employed by me for **40** securing the tramway suspension bars to the spring plank comprise, at each end of said plank, two hangers hooked over the opposite upper edges of the plank and extending suitably below the plank and two jointed **45** toggle lever arms pivotally secured at their outer ends, whereon are formed eccentrics, to the lower ends of said hangers and adapted when pressed upwardly at their jointed inner ends to cause said eccentrics **50** to firmly bind or clamp the tramway bars against the lower surface of the spring plank, the force created by said eccentrics also exerting a downward pull on the hangers to effect a secure engagement of the up-

per ends of the same with the upper opposite edges of the spring plank. When the jointed inner ends of the toggle arms are pressed upwardly to bind the eccentrics against the tramway bars, said ends pass beyond the center line of the pivots at the **60** outer ends of said arms and thereby the toggle arms become locked in their operative position. The details of said hangers and said toggle arms and of the formation of the tramway bars at said eccentrics will be **65** described hereinafter. The safety guard bars or links are articulated at their inner ends to the aforesaid hangers and at their outer ends to the outer ends of the tramway bars and said guard bars yield with the **70** tramway bars.

My invention is applicable to four-point suspension tramway-bars of various known types and hence is not limited to the specific tramway bars shown in my aforesaid Letters Patent and in connection with which, by way of illustration, I present my invention herein.

The invention will be fully understood from the detailed description hereinafter **80** presented, reference being had to the accompanying drawings, in which:

Fig. 1 is a top view of a portion of a car-truck equipped with four-point suspension features embodying my invention; **85**

Fig. 2 is a vertical longitudinal section through the same taken on the dotted line 2-2 of Fig. 1;

Fig. 3 is a plan view of one of the double suspension spring tramway bars; **90**

Fig. 4 is a side view of the same;

Fig. 5 is a detached plan view of one of the safety guard link-bars which extend from stationary means, above the end portions of the brake-beam and the tramway **95** bars and are detachably connected with the outer ends of said tramway bars;

Fig. 6 is a side view of the same;

Fig. 7 is a plan view of one of the toggle eccentric clamping arms, being the left hand **100** one of said arms looking at Fig. 2;

Fig. 8 is a side view of the same;

Fig. 9 is a plan view of the other toggle eccentric clamping arm, being the right hand **105** one looking at Fig. 2;

Fig. 10 is a side view of the same;

Fig. 11 is an end view of the same, taken from the right hand end of Fig. 10;

Fig. 12 is a side view of one of the hangers suspended from the upper edges of the spring plank or channel and to whose upper ends the inner ends of the safety guard link-bars are hinged, while to whose lower ends the outer eccentric ends of the toggle clamping arms are pivotally secured, and

Fig. 13 is a face view of the same, taken from the right hand side of Fig. 12.

10 In the drawings 10 designates a portion of a customary spring-plank or channel constituting a portion of a car-truck frame, and 11 indicates a portion of a usual type of trussed brake-beam, the parts of the beam represented being the compression member 12 and tension member or truss rod 13.

15 I illustrate the mechanism of my invention as applied to one end portion of the spring plank 10, and it will be understood that a 20 duplicate set of this mechanism will be applied to the other end portion of said spring plank, according to usual practice with respect to inside hung brakes.

25 The tramway suspension bar 14 may be of double type, as shown, that is the formation of two upwardly and outwardly inclined tramway members 15, 16 respectively from a single bar of steel, whose middle portion 17 is flat and clamped against the 30 bottom of the spring plank 10. In the present instance the outer end portions of the tramway members 15, 16 are shown as upwardly convexed to receive the adjacent portions of the truss rods, as described in my aforesaid Letters Patent, but this particular formation of said members is not essential to my present invention.

35 The flat middle portion 17 of the bar 14 extends substantially the full width of and 40 engages throughout its length the flat bottom surface of the spring plank 10, and said bar 14 at the ends of said flat portion 17 is convexly curved outwardly, as at 18, and then downwardly, as at 19, and thence the 45 end portions of the bar incline upwardly and outwardly to form the members 15, 16. The curvatures 18 form bearing surfaces for eccentrics 20 hereinafter described. The 50 tramway bars may be applied to either or both sides of the spring plank and when employed at both sides of the spring plank the tramway members 15, 16 may be conveniently formed from a single steel bar. The members 15, 16 may however be formed 55 from separate bars, and in that event the inner ends of said bars will be overlapped and applied to the spring plank and clamped thereto by the means constituting the present invention. An example of independent 60 tramway bars whose inner ends overlap and are bound to the spring plank, is shown in my pending application for Letters Patent filed February 11, 1924, Serial No. 691,888. The advantage of having the tramway bars 65 in two separate pieces is that either bar may

be adjusted longitudinally to meet conditions that may exist in the trucks, especially old trucks, to which the bars are applied. For new work, the tramway bars 14 will preferably each be in one integral piece, as shown. 70

15, 16 is formed a transverse opening 21.

20 The clamping mechanism for securing the tramway bars, comprises two steel hangers 23, 24 respectively, and two toggle lever 75 arms 25, 26, respectively, on whose outer ends are formed the eccentrics 20 hereinbefore referred to. The toggle arms may be drop forgings but will preferably be of 80 pressed steel, as shown.

25 The hangers 23, 24 are alike in construction and each comprises a vertical plate or body portion containing in its lower part a commodious opening 126 (Fig. 3) of somewhat greater width than the tramway 85 bar 14 and having at opposite sides of said opening the depending arms 27 on whose lower ends are formed hinge-knuckles 28 which lie off from the vertical plane of said arms (Fig. 12). At their upper ends, each hanger has at its upper edge two corresponding hooks 29 and, between said hooks, an upwardly extending central arm 30 on whose upper end is formed a hinge-knuckle 31 which is offset or lies off from the vertical plane of the body of the hanger, as shown in Fig. 12. The knuckle 31 projects from one side of the hanger and the knuckles 28 project from the opposite side of the hanger and are below the hooks 29. 90

30 The hangers 23, 24 are by means of the hooks 29, hung upon the opposite upper outer edges of the spring plank 10, as shown in Fig. 2, and hence in assembling the parts of the mechanism, the hangers 23, 24 will 105 have their sides carrying the hooks 29, faced toward each other, and this will leave the knuckles 31 at the upper ends of the hangers projecting outwardly in opposite directions and the knuckles 28 at the lower ends of the hangers projecting inwardly toward each other. 110

35 The toggle arm 25 (Figs. 7 and 8) has an upper web portion 32 and side flanges 33 and at its outer end said arm is formed 115 with the upwardly projecting curved eccentric 20. At the inner end of the arm 25 the web 32 is recessed to form two corresponding knuckle arms 34, which have flat parallel outer faces and are transversely apertured, at 35, to receive a pivot pin or pintle 36. The sides of the arm 25 diverge outwardly from the arms 34 to form an arm 25 of adequate strength and width and an eccentric 20 of a width substantially equal to that of the flat portion 17 of the tramway bar 14 (Fig. 7). The outer end of the arm 25 is transversely apertured, at 36, below the eccentric 20 to receive the rivet 37. The outer end of the arm 25 freely fits 120

between the lower portions of the arms 27 on the hanger 23, with its apertures 36 in line with the openings in the knuckles 28 thereof, and said arm 25 is hingedly connected with said hanger by means of the aforesaid rivet 37 which passes through said apertures and knuckles and is headed on its outer ends (Figs. 1 and 2).

The toggle arm 26 (Figs. 9, 10, 11) has an upper web portion 38 and side flanges 39 and at its outer end said arm is formed with the upwardly projecting curved eccentric 20. At the inner end of the arm 26 the web 38 is recessed to form two parallel arms 40 which are transversely apertured, at 41, and receive between them the arms 34 on toggle member 25, with the apertures 35 thereof in line with the apertures 41 in said arms 34. The pin 36 hereinbefore referred

to, extends through the apertures 35, 41 and hinges the toggle arms 25, 26 together, and preferably said pin is held in place by cotter-pins 42 so as to be removable, thereby allowing the separation of the arms 25, 26.

The sides of the arm 26 diverge outwardly from the arms 40 to form an arm 26 of adequate strength and width and an eccentric 20 thereon of a width substantially equal to that of the flat portion 17 of the tramway bar 14. The outer end of the arm 26 is transversely apertured, at 42, below the eccentric 20 and freely fits between the lower portion of the arms 27 on the hanger 24, with the apertures 42 in line with the openings in the knuckles 28 of said arms, and said arm is hingedly connected with said hanger by means of a rivet 43 which passes through said knuckles and apertures and is headed on its ends (Figs. 1 and 2).

The safety guard bars or links are numbered 44, and said bars are at their inner ends recessed to straddle the knuckles 31 on the upper extremities of the hangers 23, 24 and formed with knuckles 45 having openings aligning with the openings in the knuckles 31 to receive pivot pins 46 by which said bars are hingedly connected with said hangers. The pins 46 are held in place by cotter keys 47, thus rendering the bars detachable from and conveniently attachable to the hangers.

The safety bars 44 extend outwardly from the hangers 23, 24 on substantially horizontal lines above the brake beams and tramway bar members 15, 16 respectively, as shown in Fig. 2, and at their outer ends turn downwardly, as at 48, to the outer ends of said members 15, 16 to which they are detachably and yieldingly articulated or connected. In the present instance I connect the outer ends of the safety bars with the outer ends of the tramway members 15, 16 by means of outwardly deflected fingers or tongues 49 formed on the safety bars entered within the openings 21 formed in the

outer ends of the tramway members 15, 16, as shown in Fig. 2. The tongues 49 are inserted into the openings 21 when the bars 44 are free of the hangers 23, 24 and held in a substantially vertical position, and thereafter the bars 44 are turned to their horizontal position and engaged with the hangers by means of the pins 46. The bars 44 are detachable from the hangers on the withdrawal of the pins 46 and may then be turned upwardly to retract the tongues 49 from the openings 21 in the tramway members 15, 16.

In assembling the mechanism hereinbefore described with the tramway bar 14 and spring plank 10, the hangers 23, 24, with the bars 44 detached, the pin 36 omitted and the toggle arms 25, 26 hanging downwardly on the rivets 37, 43 respectively are hung upon the opposite flanges of the spring plank in the position shown in Fig. 2, and thereupon the tramway bar 14 is passed through the openings 126 in the hangers and above the eccentric ends of the toggle arms and positioned with its flat middle portion 17 against the bottom of the spring plank, after which the free ends of the toggle arms are swung toward each other and brought together and when said ends are slightly below a center line through the rivets 37, 43 the pin 36 is applied to said ends, and thereupon said ends of said toggle arms are forced upwardly above said center line to the position shown in Fig. 2, this causing the meeting ends of the arms to press against the center of the tramway bar and the eccentrics 20 to engage said bar at the ends of the flat portion 17 thereof and at the seats formed by the curvatures 18 in said bar and firmly clamp said bar against the spring plank. The force exerted by the eccentrics also acts to pull downwardly on the hangers 23, 24 and to rigidly secure the hangers in their position on the spring plank. If desired, in lieu of first positioning the hangers 23, 24 on the spring plank and then slipping the tramway bar 14 through the openings 126 therein, the tramway bar may first be positioned against the spring plank and the hangers 23, 24 slid, at the openings 126, over the outer ends of said bar and to the opposite sides of the spring plank, upon which they will then be hung, and thereafter the toggle arms will be connected together and closed to their operative position, as hereinbefore described.

The hangers and toggle arms afford very efficient means for securing the tramway bars to the spring plank, and it is to be noted that neither the spring plank nor the tramway bar has rivet or bolt holes formed therein as aids to securing the tramway bar.

The eccentrics 20 when in operative position project outwardly slightly beyond the vertical planes of the adjacent sides of the spring plank and thereby afford adequate

supports for the inner ends of the tramway members 15, 16 and provide rounded surfaces on which said members may press when having their yielding movements. The engagement of the eccentrics 20 with the tramway bar outwardly beyond the sides of the spring plank, also results in the hangers 23, 24 being drawn downwardly with a spring pressure against said sides.

10 The hangers 23, 24 and tramway bar 14 may be detached from the spring plank by first forcing the inner ends of the toggle arms 25, 26 downwardly below the center line of the rivets 37, 43 and then withdrawing the pivot pin 36, this leaving the hangers disconnected, the tramway bar free to be withdrawn and the hangers free to be detached from the spring plank.

When the parts are in their operative 20 position, the arms 27 on the hangers 23, 24 engage the tramway bar at its opposite side edges and prevent any transverse shifting of said bar, and said bar by reason of the downwardly convexed curvatures or bends 25 19 therein and by the presence of the eccentrics 20 are prevented from having longitudinal shifting movement.

The clamping mechanism hereinbefore described is effective for securing the tramway bars 14 without the presence of the safety guard bars 44, but I prefer to combine said bars 44 with said mechanism, as shown. The hangers 23, 24 afford adequate means for yieldably receiving and 30 supporting the inner ends of the bars 44 and permitting the detachment of said bars without disturbing the relation of the hangers to the spring plank or to the tramway bar. In addition the bars 44 are of 40 great benefit in holding the brake-beam captive in the event of accident to the brake-hangers, and further in the event of no accident to the brake-hangers but to one or both of the hangers 23, 24 or toggle 45 arms 25, 26 or their pivotal connections, whereby the hangers 23, 24 might become loosened from the spring plank, the bars 44 will become arrested on the compression member 12 of the beam or beams and act 50 to support the disabled clamping mechanism and prevent the same from falling to the track. By connecting the bars 44 with the clamping mechanism for the tramway bar, said bars 44 always become properly 55 positioned with relation to the tramway bar and are shiftable with the clamping mechanism along the spring plank to the most effective location for the tramway bar.

What I claim as my invention and desire 60 to secure by Letters Patent, is:

1. In a car-truck having a spring plank and a trussed brake-beam, a tramway suspension-bar extending below the bottom of the spring plank and inclined upwardly and 65 outwardly therefrom, and clamping means

for detachably securing said bar against said plank comprising hangers engaged upon the upper opposite edges of the plank and extending downwardly at the sides thereof, toggle arms hinged at their outer 70 ends to the lower ends of said hangers and being at said ends provided with eccentrics disposed below that portion of said bar which is below the spring plank and means pivotally connecting the inner ends of said arms, the inner ends of said arms being adapted to be forced upwardly above a center line for locking the clamping means in position and causing said eccentrics to bind said bar against the spring plank. 75

2. In a car-truck having a spring plank and a trussed brake-beam, a tramway suspension-bar extending below the bottom of the spring plank and inclined upwardly and outwardly therefrom, and clamping means for detachably securing said bar against said plank comprising hangers engaged upon the upper opposite edges of the plank and extending downwardly at the sides thereof, toggle arms hinged at their outer ends to the lower ends of said hangers and being at said ends provided with eccentrics disposed below that portion of said bar which is below the spring plank and means pivotally connecting the inner ends of said arms, the inner ends of said arms being adapted to be forced upwardly above a center line for locking the clamping means in position and causing said eccentrics to bind said bar against the spring plank. 80

85

3. In a car-truck having a spring plank and a trussed brake-beam, a tramway suspension-bar extending below the bottom of the spring plank and inclined upwardly and outwardly therefrom, and clamping means for detachably securing said bar against said plank comprising hangers engaged upon the upper opposite edges of the plank and extending downwardly at the sides thereof, toggle arms hinged at their outer ends to the lower ends of said hangers and being at said ends provided with eccentrics disposed below that portion of said bar which is below the spring plank and means pivotally connecting the inner ends of said arms, the inner ends of said arms being adapted to be forced upwardly above a center line for locking the clamping means in position and causing said eccentrics to bind said bar against the spring plank. 90

3. In a car-truck having a spring plank and a trussed brake-beam, a tramway suspension-bar extending below the bottom of the spring plank and inclined upwardly and outwardly therefrom, and clamping means for detachably securing said bar against said plank comprising hangers engaged upon the upper opposite edges of the plank and extending downwardly at the sides thereof, toggle arms hinged at their outer ends to the lower ends of said hangers and being at said ends provided with eccentrics disposed below that portion of said bar which is below the spring plank and means pivotally connecting the inner ends of said arms, the inner ends of said arms being adapted to be forced upwardly above a center line for locking the clamping means in position and causing said eccentrics to bind said bar against the spring plank, 135

and said suspension bar being curved downwardly at the outer sides of the said eccentrics.

4. In a car-truck having a spring plank 5 and a trussed brake-beam, a tramway suspension-bar extending below the bottom of the spring plank and inclined upwardly and outwardly therefrom, and clamping means for detachably securing said bar against said 10 plank comprising hangers engaged upon the upper opposite edges of the plank and extending downwardly at the sides thereof, toggle arms hinged at their outer ends to the lower ends of said hangers and being at said 15 ends provided with eccentrics disposed below that portion of said bar which is below the spring plank and a pin extending through overlapping portions of the inner ends of said arms, said pin being removable, and the 20 inner ends of said arms being adapted to be forced upwardly above a center line for locking the clamping means in position and causing said eccentrics to bind said bar against the spring plank.
5. In a car-truck having a spring plank 25 and a trussed brake beam, a tramway suspension-bar extending below the bottom of the spring plank and inclined upwardly and outwardly therefrom, clamping means suspended from the upper edges of the spring 30 plank and extending beneath that portion of said bar which is below the spring plank for binding the bar against said plank and a safety guard bar articulated at its inner end 35 to said clamping means and at its outer end to the outer end of the suspension bar, said guard bar being disposed above the brake-beam and the suspension bar.
6. In a car-truck having a spring plank 40 and a trussed brake beam, a tramway suspension-bar extending below the bottom of the spring plank and inclined upwardly and outwardly therefrom, clamping means supported from and shiftable along the spring 45 plank and extending beneath that portion of said bar which is below the spring plank for binding the bar against said plank and a safety guard bar articulated at its inner end 50 to said clamping means and at its outer end to the outer end of the suspension bar, said guard bar being disposed above the brake-beam and the suspension bar.
7. In a car-truck having a spring plank 55 and a trussed brake beam, a tramway suspension-bar extending below the bottom of the spring plank and inclined upwardly and outwardly therefrom, clamping means supported from and shiftable along the spring 60 plank and extending beneath that portion of said bar which is below the spring plank for binding the bar against said plank and a safety guard bar articulated at its inner end 65 to said clamping means and at its outer end to the outer end of the suspension bar, said guard bar being disposed above the brake-

beam and the suspension bar and detachable from said clamping means and said suspension bar without disturbing either the clamp or bar.

8. In a car-truck having a spring plank 70 and a trussed brake beam, a tramway suspension-bar extending below the bottom of the spring plank and inclined upwardly and outwardly therefrom, clamping means suspended from the upper edges of the spring 75 plank and extending beneath that portion of said bar which is below the spring plank for binding the bar against said plank and a safety guard bar articulated at its inner end 80 to said clamping means and at its outer end to the outer end of the suspension bar, said guard bar being disposed above the brake-beam and the suspension bar, and said clamping means comprising plates having hooks engaged upon the upper opposite 85 edges of the spring plank and toggle levers carried by said plates and having eccentrics below the suspension bar to bind the same against the spring plank.

9. In a car-truck having inside-hung 90 trussed brake-beams, a spring plank and tramway suspension-bars extending longitudinally of the truck below said plank and inclined at their end portions upwardly and outwardly therefrom, clamping means for 95 binding the middle portions of the suspension bars against the bottom of said plank comprising hangers hung from the upper portions of the spring plank and extending below the sides of the same, toggle arms 100 hinged at their outer ends to the lower ends of said hangers and being at said ends provided with eccentrics below that portion of the suspension bar which is below said plank and means pivotally connecting the inner 105 ends of said toggle arms, the inner ends of said arms being adapted to be forced upwardly above a center line for causing the eccentrics to bind the suspension bar against the spring plank and exert a downward 110 clamping action on said hangers to bind them in position on the spring plank.

10. In a car-truck having inside-hung 115 trussed brake-beams, a spring plank and tramway suspension-bars extending longitudinally of the truck below said plank and inclined at their end portions upwardly and outwardly therefrom, clamping means for 120 binding the middle portions of the suspension bars against the bottom of said plank comprising hangers hung from the upper portions of the spring plank and extending below the sides of the same, toggle arms hinged at their outer ends to the lower ends of said hangers and being at said ends provided with eccentrics below that portion of the suspension bar which is below said 125 plank and means pivotally connecting the inner ends of said toggle arms, the inner ends of said arms being adapted to be forced 130

upwardly above a center line for causing the eccentric to bind the suspension bar against the spring plank and exert a downward clamping action on said hangers to bind them in position on the spring plank, and said eccentric being located below the sides of the spring plank and affording broad curved surfaces on which the tramway members may bear during their yielding movements.

11. In a car-truck having inside-hung trussed brake-beams, a spring plank and tramway suspension-bars extending longitudinally of the truck below said plank and inclined at their end portions upwardly and outwardly therefrom, clamping means for binding the middle portions of the suspension bars against the bottom of said plank comprising hangers hung from the upper portions of the spring plank and extending below the sides of the same, toggle arms hinged at their outer ends to the lower ends of said hangers and being at said ends provided with eccentric below that portion of the suspension bar which is below said plank and means pivotally connecting the inner ends of said toggle arms, the inner ends of said arms being adapted to be forced upwardly above a center line for causing the eccentric to bind the suspension bar against the spring plank and exert a downward clamping action on said hangers to bind them in position on the spring plank, said eccentric being disposed below the sides of the spring plank and projecting slightly beyond the vertical plane of the same and affording broad curved surfaces

on which the tramway members may bear and said members being curved downwardly at the outer sides of said eccentric.

12. In a car-truck having inside-hung trussed brake-beams, a spring plank and tramway suspension-bars extending longitudinally of the truck below said plank and inclined at their end portions upwardly and outwardly therefrom, clamping means for binding the middle portions of the suspension bars against the bottom of said plank comprising hangers hung from the upper portions of the spring plank and extending below the sides of the same, toggle arms hinged at their outer ends to the lower ends of said hangers and being at said ends provided with eccentric below that portion of the suspension bar which is below said plank and means pivotally connecting the inner ends of said toggle arms, the inner ends of said arms being adapted to be forced upwardly above a center line for causing the eccentric to bind the suspension bar against the spring plank and exert a downward clamping action on said hangers to bind them in position on the spring plank, said eccentric being located below the sides of the spring plank and affording broad curved surfaces on which the tramway members may bear during their yielding movements, and said hangers having openings above said eccentric through which the tramway bar extends.

Signed at New York city, in the county of New York and State of New York, this 11th day of February, A. D. 1924.

SETH A. CRONE.
